CLOSURE FOR CONTAINERS

Ralph W. Wilson, New York, N. Y.

Application November 23, 1935, Serial No. 51,208

3 Claims. (Cl. 221—16)

This invention relates to closures for containers and particularly containers used for liquid or emulsified cosmetic preparations. More particularly, the invention is concerned with the provision of a closure which will prevent the accidental escape of the preparation within the container but which will permit its convenient dispensing without manual manipulation of a cap, plug, valve or the like. In accordance with the underlying principle of the invention the closure comprises generally a yielding member provided with an opening which is normally held closed by the stresses within the yielding member itself and with cooperating non-yielding means by which pressure may be applied to the yielding member to distend the opening and permit the escape of the preparation therethrough with more or less freedom. Closures now available are usually provided with valves or caps to close the opening. Such closures can be used only after the valve or cap is manipulated. The present invention requires no manipulation of a cap or valve but on the contrary permits the closure to be opened by pressing the device against the palm of the hand into which the preparation is to be dispensed. When the pressure is relieved the opening automatically closes and when the pressure is applied the opening automatically is opened.

Reference is now to be had to the accompanying drawing for an understanding of two embodiments of the invention which will illustrate its principle.

In the drawing:

Figure 1 is a view in vertical section of the improved closure showing a fragment of a container to which it is applied.

Figure 2 is a view in perspective of the improved closure shown in Figure 1 and illustrating the elongated discharge opening.

Figure 3 is a view in vertical section showing another form of the device made in accordance with the invention and illustrating a fragment of a container to which it is applied.

Figure 4 is a view in perspective showing the device illustrated in Figure 3.

The container *a* has attached thereto by any convenient means such as threads *a'*, a non-yielding plastic neck member *b*. Corrugations *b'* may be provided to facilitate application of the member *b* to the container. A yielding gasket *c* may be interposed between the container and the neck member *b* for sealing purposes as will be understood. The end of the cap *b* may be of frusto-conical form as indicated at

*b*², a central discharge opening *b*³ being formed therein. A yielding closure *d* of rubber or other suitable material is mounted on the cap member *b*. The closure *d* is retained in place by a suitable cap *e* which may be engaged permanently with the neck member *b* as by turning in the lower edge to engage a shoulder *b*⁴ of the neck. The end of the cap member *e* has a circular opening *e'* therein to expose the central portion of the yielding closure *d*. This closure member *d* may be moulded so that the exposed portion of the closure *d* will extend through the opening *e'* while the portion *d'* of the closure which is not exposed will lie under the cap. In the closure *d* is formed a dispensing opening *d*² in line with the opening *b*³ in the neck member *b*. The opening *d*² is preferably of elongated form as illustrated. The underface of the closure *d* may be moulded so as to seat snugly on the upper end of the neck member *b* so that the parts are centered and held in fixed interrelation.

In use, it will be evident that when the cap *e* is moved downwardly on the neck member *b* tension will be applied within the yielding closure *d* so as to distend the opening *d*². This condition can be most conveniently effected by pressing the closure *d* and cap *e* against the palm of the hand at which time the container is tilted and its contents will be dispensed into the palm of the hand. When the pressure is released the resiliency of the closure *d* which has been deformed will restore the parts to their normal relation, urging the cap *e* upwardly, and the stresses within the yielding closure will force the material at the opening *d*² into abutment and close the opening automatically.

The embodiment illustrated in Figure 3 includes a container *f* to which is secured a neck piece *g* by any suitable means such as threads *f'*. The closure comprises a hollow yielding member *h* of bulbous form, the base being moulded with a circular flange *h'* which may be disposed between the container *f* and neck piece *g* to constitute a sealing gasket. The closure member *h* at its lower side has a central opening *h*² to admit the preparation within the container when it is inverted. At its upper side the closure member *h* has a dispensing opening *h*³ which is preferably in line with the opening *h*². The bulbous member is partially encased by a cylindrical cover *i* having a circular flange *i'* at its inner end adapted to engage a shoulder *g'* within the neck member *g* to limit the outward movement of the cover. The cover is movable inwardly with respect to the neck member *g* and

also with respect to the yielding bulbous closure h . The upper end of the cover is preferably concave in cross section and formed with a central opening i^2 extending around the dispensing opening h^3 in the closure h .

In the use of the device it will be evident that pressure on the cover i will move it inwardly so as to set up stresses within the yielding closure h serving to separate the material at the opening h^3 and permit discharge of the contents of the container. At the same time, the yielding material of the closure will be deformed adjacent to the central opening h^2 and this opening will be reduced commensurately in area. In fact, it is possible at least theoretically to close the opening h^2 in such manner and prevent the flow of the preparation within the container to the interior of the bulbous closure h while at the same time the material within this closure is dispensed through the discharge opening h^3 .

The embodiment shown in Figure 3 lends itself very conveniently to the dispensing of the preparation within the container by pressure of the improved closure against the palm of one hand while the container is inverted. The cover i can be pressed firmly against the palm of the hand and thereby moved inwardly to bring about the opening of the discharge opening h^3 . When the pressure is released the elasticity of the bulbous closure member h will restore it to normal shape, the internal stress serving to seal the opening h^3 and move the cover i outwardly until its movement is checked by the engagement of the flange i' with the shoulder g' .

Other embodiments of the principle may be made by those skilled in the art without departing from the invention which is defined in the appended claims.

I claim as my invention:

1. In combination with a container for fluids a closure therefor comprising a neck member secured thereto, a yielding closure element mounted in the neck member and having a portion secured between said neck member and said

container to form a sealing gasket and having a dispensing opening normally closed by the resiliency of the material and a non-yielding member enclosing said yielding element and slidably mounted with relation to the said yielding closure element and said neck member to effect separation of the yielding material at the opening and cooperating means carried by the neck member and the said slidable member to limit the movement of said member.

2. A closure comprising a closure member of yielding non-metallic material having an opening therein normally closed by the resiliency of the said material, and a non-yielding hollow cover in which the yielding closure is received, the cover being movably mounted and having a portion overlying the yielding closure member and formed with a central opening surrounding the dispensing opening in the said closure member whereby movement of the cover in one direction will cause separation of the yielding material at the dispensing opening.

3. A closure comprising a closure member of yielding non-metallic material having an opening therein normally closed by the resiliency of the said material, and a non-yielding hollow cover in which the yielding closure is received, the cover being movably mounted and having a portion overlying the yielding closure member and formed with a central opening surrounding the dispensing opening in the said closure member, said central opening being larger than the greatest dimension of the opening in the yielding material, whereby movement of the cover in one direction will cause separation of the yielding material at the dispensing opening by engaging the yielding material beyond the limits of the opening therein and flexing the material adjacent the last named opening into the central opening of the non-yielding member, whereby the yielding material will lie wholly beneath the cover and serve to urge the same upwardly yieldingly.

RALPH W. WILSON.
